UNITED STATES PATENT OFFICE.

HENRY T. ADAMS, OF CHICAGO, ILLINOIS.

ADJUSTABLE RING BOOK.

Application filed January 29, 1927. Serial No. 164,524.

This invention relates to adjustable ring books and the like for holding sheets of perforated paper and is an improvement on the ring book described and claimed in my former 5 Patent No. 1,593,416 granted July 20, 1926.

The invention is fully described in the following specification and shown in the accompanying drawings, in which:

Figure 1 is a front elevation of the back 10 strip showing two of the rings in place therein;

Fig. 2 is a partial enlarged end elevation of the same in a book;

Fig. 3 is a side elevation of the hinge end 15 of a ring; and

Fig. 4 is a similar view of the other end of the ring.

The embodiment illustrated comprises a metal back strip A adapted to receive a number 20 of detachable rings B. The back strip has a longitudinal rib 10 formed on each side of a flat central portion 11. Each rib continues as an inwardly turned edge which is substantially C-shaped in cross-section, there- 25 by providing a longitudinal channel 12 open along an inner edge 13.

The flat portion 11 lies in substantially the same plane as the bottoms of the channels 12. Fig. 2 shows a partial end view of a book 30 in which the strip A is secured to a filler strip C and a flexible cover D by means of two or more rivets E.

The ring is U-shaped in side elevation as shown in Fig. 2 and is made from a strip of 35 metal of uniform width throughout. One end is formed into a transverse roll 14 which is adapted to slide into either of the channels 12 so that the ring B may be rocked about the center of this roll as an axis.

The central portion 15 of the ring B is 40 made U-shaped in transverse section so as to conform on the inner side to the shape of the holes in the sheets of paper (not shown) through which the rings are placed in a well-known manner. The outer end of the ring B is curved outwardly at 16 and the center of this end is forced outwardly at 17 so as to just pass through the opening 13 and to engage the inturned edge. In order to snap 45 the ring in place, it is necessary for the operator to press inwardly on its outer end 16. To release it, he pulls upwardly upon it and may at the same time, if desired, press inwardly on the outer end of the ring.

The rings B are inserted at either end of 50 the channel 12 and are slid along to the de-

sired position and are rocked over into engagement with the opposite rolled edge. While only two rings are here shown, any desired number and spacing arrangement may 60 be used.

Where the metal used in the rings is very heavy, the outer end of each ring must be forced to one side, i. e. longitudinally of the back strip A until it passes into the longitudinal channel 12, after which it is released. 65

Thus, it will be seen, a very efficient, convenient and substantial ring book is provided and one which can be manufactured 70 economically. The use of the ribs adds very greatly to the strength and stiffness of the whole for a given weight of metal and the location of a rib adjacent one of the curved outer edges provides an opening 13 which is 75 placed at a particularly advantageous position for the insertion and operation of the ring member B.

While I have shown and described but a single embodiment of this invention, it is to 80 be understood that it is capable of many modifications. Changes therefore in the construction and arrangement may be made which do not depart from the spirit and scope of the invention as disclosed in the 85 appended claims.

I claim:

1. In a ring book, a metal back strip having 90 inturned edges and an integral longitudinal rib along one side forming a longitudinal channel, and a U-shaped ring-member adapted to slide into said longitudinal channel and to be rotatably secured therein, the other end of said ring-member being adapted to swing into interlocking relation with the 95 other edge.

2. In a ring book, a metal back strip having inturned edges and an integral longitudinal rib along one side forming a longitudinal channel, and a U-shaped ring-member having 100 one end rolled and adopted to slide into said longitudinal channel and to be rotatably secured therein, the other end of said ring-member being adapted to swing into interlocking relation with the other edge. 105

3. In a ring book, a metal back strip having inturned edges and a longitudinal rib along each side, the side of each rib and the inturned edge forming a longitudinal groove of C-shaped cross-section, and a U-shaped ring-member adapted to hingedly interlock 110 with one of said edges and its adjacent rib,

the other end of said ring-member being adapted to interlock with the other edge.

4. In a ring book, a metal back strip having inturned edges and a longitudinal rib along each side, the side of each rib and the in-turned edge forming a longitudinal groove of C-shaped cross-section, the central portion of said strip being substantially flush with the back of said edge portions, and a 10 U-shaped ring-member adapted to hingedly interlock with one of said edges and its adjacent rib, the other end of said ring-member being adapted to interlock with the other edge.
- 15 5. In a ring book, a metal back strip having inturned edges and an integral longitudinal rib along one side, and a U-shaped ring-

member formed from a strip of metal of uniform width throughout, one end of the strip being rounded to rotatably fit in one of said 20 inturned edges and its adjacent rib.

6. In a ring book, a metal back strip having inturned edges and an integral longitudinal rib along one side, and a U-shaped ring-member formed from a strip of metal of uniform 25 width throughout, one end of the strip being rounded to rotatably fit in one of said in-turned edges, and its adjacent rib, the center of said strip being substantially semi-circular, the center of the other end being struck 30 up so as to form a catch to engage the other other edge of the back strip.

HENRY T. ADAMS.
